UNITED STATES PATENT OFFICE.

JAMES L. GRAHAM, OF ALLEGHENY, PENNSYLVANIA.

VALVE FOR AUTOMATIC WATER-HEATERS.

SPECIFICATION forming part of Letters Patent No. 699,798, dated May 13, 1902.

Application filed December 21, 1901. Serial No. 86,775. (No model.)

To all whom it may concern:

Be it known that I, JAMES L. GRAHAM, a resident of Allegheny, in the county of Allegheny and State of Pennsylvania, have invented a new and useful Improvement in Valves for Automatic Water-Heaters; and I do hereby declare the following to be a full, clear, and exact description thereof.

My invention relates to automatic water-heaters, and more especially to the valve for controlling the flow of gas to the burners of the heater.

Among the objects of my invention are to provide a valve for this purpose which is adjustable to adapt it to different water-pres-
15 sures and which is constructed to be closed by the pressure of gas alone, so that it will automatically cut off the flow of gas to the burners when the water is not running or is
20 entirely cut off.

A further object of my invention is to construct a valve for this purpose having dia-
25 phragms for receiving the water-pressure, so that said diaphragms cannot easily wear out
or burst.

A further object of my invention is to pro-
30 vide regulating cocks or valves in the water-
pipe, so that the amount of gas flowing to
the burners can be accurately adjusted to cor-
35 respond to the amount of water to be heated
and so that when the latter is increased the
gas will be automatically increased in propor-
tion thereto.

A further object of my invention is to im-
35 prove a valve of this character in details of
construction, as will hereinafter appear.

In the accompanying drawings, Figure 1 is a vertical section through my valve, showing the same full size. Fig. 2 is a side view of
40 the valve with the pipe connections, showing the same half size; and Fig. 3 is a vertical section of a modification.

The water-supply pipe is shown at 1, the
45 gas-supply pipe at 2, and the gas-regulating
valve at 3. This valve comprises a suitable
casing or body 4, having heads 5 and 6 and
inclosing the chamber 7. Through the heads
5 and 6 suitable connections 8 and 9 are made
50 to the water-supply pipe, as shown. In the
chamber 7, adjacent to each of the heads, are
the diaphragms 10 and 11, which receive the
water-pressure through the connections 8 and

9, respectively. In lieu of these diaphragms
any other movable parts, such as pistons 10^a
and 11^a, (shown in Fig. 3,) might be employed;
55 but the diaphragms are much cheaper to con-
struct and more easily applied so as to pre-
vent leakage. I therefore prefer to use dia-
phragms. When pistons are used, they will
be provided with stems 30, which are guided
60 in yokes 31 in the heads 5 and 6 in order to
keep the pistons from binding.

The chamber 7 is divided by the web 12,
through which is the gas-passage 13, and on
the upper face of said ledge is formed a seat
14 for the gas-valve 15. The gas-supply pipe
2 communicates with the chamber 7 below the
valve-seat 14, while connected to the cham-
ber above said seat is the gas-pipe 16, which
leads to the main burners of the water-heater.
70 A small pipe 17 leads from the chamber be-
low the valve-seat to the pilot-burner.

The gas-valve 15 comprises a disk 18, hav-
ing secured thereto the leather or other soft
disk 19, which is adapted to rest upon the
75 seat 14. Formed integral with the disk 18
or suitably secured thereto and projecting in
opposite directions are the stems 20 and 21,
to the outer ends of which are suitably se-
cured the disks or pistons 22 and 23, which
80 are substantially the same size as the cham-
ber 7 and work fairly closely therein. These
pistons or disks are in such proximity to the
diaphragms 10 and 11 that the water-pressure
on the diaphragms will carry the latter against
85 these disks or pistons to move the valve, as
will hereinafter more fully appear. The pis-
ton 23 has a greater area than the gas port
or passage 13, so that the gas in the lower
part of the chamber 7 will exert a greater
90 pressure downward on the disk 23 than up-
ward on the valve 15. Consequently when
the water-pressures on the two diaphragms
10 and 11 are balanced the pressure of the
gas in the chamber 7 on what may be termed
95 a "differential" piston 15 and 23 will hold
the valve 15 to its seat, thus shutting off the
gas from the main burners of the heater.

In order to adjust the valve to different
water-pres-
100 sures, the pistons 22 and 23 are se-
cured to the stems 20 and 21, so that they
can be adjusted up and down. Any suitable
adjusting means for this purpose may be em-
ployed; but I prefer to thread the stems 20

and 21, as shown, and have them project into threaded sleeves on the pistons, so that by turning the latter on the stems they will be adjusted either up or down, as desired. Screws 5 25 are passed through openings in the heads of the pistons 22 and 23 and work in threaded axial openings in the stems 20 and 21. These screws are tightened after the pistons have been adjusted to the desired position and 10 lock the pistons in position.

In the water-supply pipe, in advance of the water connection 9, is a supply-regulating valve or cock 26, that shown in the drawings being an ordinary plumber's waste-cock, although any other form of valve might be used. Also in said water-supply pipe, between the connections 8 and 9, is a regulating-valve 27, that shown being an ordinary globe-valve, although a valve of any other type or a mere 15 two-way or waste cock might be used. Beyond the connection 8 the water-pipe leads at 28 to the coil in the heater.

The operation of the valve is as follows: The valve having been properly adjusted, as 25 long as the water is not flowing through the coil the pressures on the diaphragms 10 and 11 will be balanced, so that the gas-pressure in the chamber 7, acting on the differential piston 15 23, will keep the valve closed and 30 prevent the gas from flowing to the main burners. A portion of the gas, however, flows from the chamber 7 through the pipe 17 to the pilot-burner. The regulating-valve 27 in all cases is so adjusted that it sometimes 35 restricts the flow of the water through the water-pipe. As soon, then, as the hot-water spigot is open and the water begins to flow in the water-pipe, by reason of this restriction by the valve 37, the water will be 40 drawn more quickly from above the diaphragm 10 than from below the diaphragm 11, thus unbalancing the pressures on the two diaphragms, the greater pressure below acting through the diaphragm 11 on the piston 45 23 and raising the valve 15 from its seat, thus permitting gas to flow to the main burners of the heater. The degree to which the valve 15 opens will depend upon the rapidity with 50 which the water is flowing from the hot-water spigot, as this determines the difference in the pressures on the top and bottom diaphragms. When the hot-water spigot is closed, the reaction of the water will be felt first above the diaphragm 10, thus closing the valve.

55 In order to adjust the valve to different water-pressures, the pistons 22 and 23 are adjusted on the stems 20 and 21. In case the water-pressure is low the piston 23 should normally lie fairly close to the diaphragm 11, 60 and generally the piston 22 is adjusted so that it is low down in the valve-chamber. With higher water-pressures, however, the piston 23, and generally also the piston 22, is elevated, since the water-pressure will act 65 more quickly and strongly on said pistons.

When the apparatus is installed, the gas will be turned on full, and the water will like-

wise be turned on full and the hot-water spigot opened. Then the cock or valve 26 will be adjusted until the desired flow of water is obtained. It will be found that in that case little or no gas will flow to the burners. This is due to the fact that the pressure on the pistons 10 and 11 is balanced, and the gas acting on the differential piston 15 23 will 70 keep the gas-valve 15 seated. The valve 27 is then adjusted, thus restricting the flow of water between the connections 8 and 9, unbalancing the pressure on the diaphragms 10 and 11. The greater pressure on the diaphragm 11 will act on the piston 23 and open the valve 15, and this opening is such that it regulates the amount of gas accurately to the quantity of water being heated. Should the user at any time wish to increase the amount 85 of hot water being heated per minute, he will merely open the valve or cock 26 wider, so as to give the increased flow of water. As soon as this is done the pressure below the diaphragm 11 will correspondingly increase by 90 reason of the restriction of the water-pipe by the valve 27. As a consequence the valve 15 will tend to open farther than it did formerly, thus permitting more gas to flow to the burners, and this increase when the parts are 95 properly adjusted will correspond to the increase of water. In this manner any desired quantity of water can be heated per minute without necessitating an adjustment of the gas-regulating valve.

100 The pistons 22 and 23 are substantially the same diameter as the chamber 7, so that they form a broad support for the diaphragms 10 and 11 and prevent the same from bursting, cutting, or wearing at the points where they bend over the corners of the casting. It has been found that by the use of these broad abutments or pistons the life of the diaphragm is greatly increased. Furthermore, the means for adjusting these pistons is such 105 that it does not destroy the smooth surface which is presented to the diaphragm, thus preventing the latter from becoming cut or worn.

110 What I claim as my invention, and desire to secure by Letter Patent, is—

1. In an automatic water-heater, the combination with a water-supply pipe and gas-supply pipe, of a valve comprising a casing having a chamber therein, a diaphragm in 115 said chamber near each end thereof, connections from the water-supply pipe to both ends of the valve-chamber outside said diaphragms, a valve for controlling the passage of the gas to the heater, and disks connected to said valve and working in said chamber adjacent to the diaphragms, whereby said diaphragms will transmit motion to said valve.

2. In an automatic water-heater, the combination with a water-supply pipe, of a valve 120 comprising a casing having a chamber therein connected to the gas-supply pipe, a valve-seat in said chamber, a disk valve co-operating with said seat and opening toward the

heater, a piston of greater area than the valve connected thereto on the side toward the gas-inlet, connections from the water-supply pipe to both ends of the valve-chamber, movable means in said chamber near each end thereof for receiving the water-pressure, and connections between said movable means and the gas-valve for transmitting the motion of the former to the latter.

10 3. In an automatic water-heater, the combination with a water-supply pipe and gas-supply pipe, of a valve comprising a casing having a chamber therein connected to the gas-supply pipe, a diaphragm in said chamber near each end thereof, connections from the water-supply pipe to both ends of the valve-chamber outside said diaphragms, a valve-seat in said chamber, a disk valve co-operating with said seat and opening toward 15 the heater, and projections on said valve and having their ends lying adjacent to the diaphragms, whereby said diaphragms will transmit motion to said valve, one of said projections carrying a piston of greater area than 20 the gas-valve, whereby when the pressure on the diaphragms is balanced the pressure of the gas will keep the valve seated.

4. In an automatic water-heater, the combination with a water-supply pipe and gas-supply pipe, of a valve comprising a casing having a chamber therein, a valve controlling the passage of gas to the heater, connections from the water-supply pipe to both ends of the valve-chamber, movable means in said 35 chamber near each end thereof for receiving the water-pressure, and adjustable connections between said movable means and the valve, whereby said movable means will transmit motion to said valve.

40 5. In an automatic water-heater, the combination with a water-supply pipe and gas-supply pipe, of a valve comprising a casing having a chamber therein, movable means in said chamber near each end thereof, connections from the water-supply pipe to both ends of the valve-chamber outside said movable means, a valve for controlling the passage of the gas to the heater, stems on said valve, and heads adjustably secured to said stems and 45 lying adjacent to diaphragms, whereby said diaphragms will transmit motion to said valve.

6. In an automatic water-heater, the combination with a water-supply pipe and gas-supply pipe, of a valve comprising a casing having a chamber therein, a diaphragm in said chamber near each end thereof, connections from the water-supply pipe to both ends of the valve-chamber outside said diaphragms, a valve for controlling the passage 55 of the gas to the heater, disks working in said chamber adjacent to the diaphragms, and adjustable connections between said disks and the valve, whereby said diaphragms will transmit motion to the valve.

65 7. In an automatic water-heater, the combination with a water-supply pipe and gas-supply pipe, of a valve comprising a casing

having a chamber therein connected to the gas-supply pipe, a valve-seat in said chamber, a disk valve co-operating with said seat and opening toward the heater, pistons working in said chamber and connected to the valve, one of said pistons being of greater area than the gas-valve, and connections from the water-supply pipe to both ends of the valve-chamber outside of the pistons.

8. In an automatic water-heater, the combination with a water-supply pipe and gas-supply pipe, of a valve comprising a casing having a chamber therein connected to the gas-supply pipe, a diaphragm in said chamber near each end thereof, connections from the water-supply pipe to both ends of the valve-chamber outside said diaphragms, a valve-seat in said chamber, a disk valve co-operating with said seat and opening toward the heater, pistons working in said chamber adjacent to the diaphragms, and connections between said pistons and the valve, one of said pistons being of greater area than the gas-valve, whereby said diaphragms will transmit motion to said valve.

9. In an automatic water-heater, the combination with a water-supply pipe and gas-supply pipe, of a valve comprising a casing having a chamber therein, a diaphragm in said chamber near each end thereof, connections from the water-supply pipe to both ends of the valve-chamber outside said diaphragms, a valve for controlling the passage of gas to the heater, said valve being provided with screw-threaded stems projecting in opposite directions, disks connected to said screw-threaded stems and working in said chamber adjacent to the diaphragms, whereby said diaphragms will transmit motion to said valve, and screws extending through said disks into openings in the ends of the stems.

10. In an automatic water-heater, the combination with a water-supply pipe and gas-supply pipe, of a valve comprising a casing having a passage therethrough for the gas, a valve for controlling said passage, connections from the water-supply pipe to opposite sides of the valve for transmitting motion to said valve, a pressure-regulating valve in the water-supply pipe between the connections leading to the valve, and a supply-regulating valve in the water-supply pipe in advance of the connections leading to the valve.

11. In an automatic water-heater, the combination with a water-supply pipe and gas-supply pipe, of a valve comprising a casing having a chamber therein connected to the gas-supply pipe, a valve-seat in said chamber, a disk valve co-operating with said seat and opening toward the heater, pistons connected to said valve and working in said chamber, one of said pistons being of greater area than the gas-valve, connections from the water-supply pipe to each end of the chamber outside said pistons, a pressure-regulating valve in the water-supply pipe between the connections leading to the valve-chamber, and a sup-

ply-regulating valve in the water-supply pipe in advance of said connections.

12. In an automatic water-heater, the combination with a water-supply pipe and gas-supply pipe, of a valve comprising a casing having a chamber therein, a diaphragm in said chamber near each end thereof, connections from the water-supply pipe to both ends of the valve-chamber outside said diaphragms, a valve for controlling the flow of the gas to the heater, disks lying adjacent the diaphragms, adjustable connections between said disks and the valve, whereby said dia-

phragms will transmit motion to said valve, a pressure-regulating valve in the water-supply pipe between the connections leading to the valve-chamber, and a supply-regulating valve in said water-supply pipe in advance of said connections. 15

In testimony whereof I, the said JAMES L. GRAHAM, have hereunto set my hand.

JAMES L. GRAHAM.
